UNITED STATES PATENT OFFICE

2,661,711

ANCHOR DAVIT

George P. Evans, Hellam, Pa.

Application October 26, 1951, Serial No. 253,347

5 Claims. (Cl. 114—210)

1

This invention relates to davits designed for lifting and lowering anchors.

The primary object of the invention is to provide an anchor davit of the portable type which may be readily and easily positioned for use, and one which may be stowed in a comparatively small space when not in use.

Still another object of the invention is to provide a portable anchor davit which may be readily and easily connected with supporting bases that may be conveniently located at various points on a deck to facilitate the handling of the ship's anchor.

Another important object of the invention is to provide an anchor davit including an arm which swivel connection with the base, so that it may be swung to various angular positions with respect to the base to facilitate the lifting and lowering of the anchor used therewith, to properly position the anchor on the deck of the ship.

Still another object of the invention is to provide an anchor davit wherein the pivoted lifting arm thereof is provided with means for gripping the lifting cable at a point adjacent to the free end of the arm, so that the pull directed to the cable in lifting the anchor may be transferred to the lifting arm, to swing the arm to a position over the deck of the vessel, permitting the anchor to be deposited on the deck of the vessel at the desired location.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings,

Figure 1 is a plan view illustrating an anchor davit constructed in accordance with the invention, as mounted on the deck of a vessel.

Fig. 2 is a view illustrating the lifting arm of the davit, in side elevation.

Fig. 3 is an enlarged elevational view showing the lifting arm in its lowermost position.

Fig. 4 is a plan view thereof.

Fig. 5 is a sectional view taken on line 5—5 of Fig. 4.

Fig. 6 is a sectional view taken on line 6—6 of Fig. 4.

Fig. 7 is a sectional view taken on line 7—7 of Fig. 3.

Fig. 8 is a perspective view of the adjustable arm stop.

2

Referring to the drawings in detail, the reference character 5 indicates the deck of a ship to which the davit base 6 is secured, the davit base 6 in the present showing being located on the bow of the ship. However, it is to be understood that it is contemplated to position several of these davit bases on the deck of the ship at various locations for convenience in operating or raising and lowering an anchor.

The davit base 6 is provided with an upstanding supporting block 7 which provides a support for the arm 8 of the davit, which is pivotally connected with the davit base 6, through the bearing plates 9 and bolt 10 that extends through the bearing plates, the bolt 10 being so arranged that it may be readily and easily removed to permit of the ready removal of the davit for stowing, when not in use.

The base 6 also is provided with a plurality of spaced openings 11 in which the pin 12 of the stop 13 is positioned, the stop being adjustable by positioning the pin 12 in any of the openings 11 to regulate the normal inclined position of the anchor davit. It will be obvious that by moving the stop 13 from the position as shown by Fig. 2, to a position near the pivot of the arm 8, the angle at which the arm 8 is normally supported, may be varied.

The base 6 is swiveled to the deck 5 of the vessel by the pivot pin 14 which is disposed in an opening in the deck. Thus it will be seen that the base may be readily and easily rotated to swing the arm 8 to a position to facilitate the operation to raise or lower the anchor.

The arm 8 comprises the inner section 15 to which the bearing plates 9 are secured, as by means of screws 16, the inner section embodying spaced bars 17 held in proper spaced relation by means of the spacers 18. The bars 17 are formed with openings elongated longitudinally of the bars, the openings being indicated by the reference character 19.

The outer section of the arm 8 embodies the bars 20 that are formed with openings through which the bolts 21 extend, the bolts 21 also passing through the elongated openings 19 of the inner section 15 so that by loosening the bolts 21, the outer section of the arm 8 may be adjusted to lengthen or shorten the arm, as desired. Nuts 22 are provided on the bolts 21 for tightening the bolts and holding the sections of the arm secure.

The reference character 23 indicates the bolt on which the pulley 24 is mounted. The bolt 23 is so arranged that when the pulley 24 is positioned thereon, the outer ends of the bars 20 will

extend beyond the edges of the pulley 24 to act as a guard to prevent the rope which is indicated by the reference character 25, and which passes thereover, from running off of the pulley when the rope is operated to raise or lower the anchor which in the present showing is indicated by the reference character 26.

Secured to one of the bars 28 of the outer section, is the rope jamb 27 which is formed of a length of strap metal bent upon itself providing a wedge-shaped opening 26, the rope jamb being bolted or otherwise secured to the outer section of the arm in such a way that it will overlie the space between the bars of the sections of the arm in direct line with the rope 25 which is used in connection with the davit.

It might be further stated that the supporting block 7 is provided with securing pins 28 which fit in openings formed in the davit base 6 so that the supporting block may be readily removed when desired.

From the foregoing it will be seen that due to the construction shown and described, I have provided an anchor davit which may be conveniently operated by a single person to raise or lower an anchor which under normal conditions, would be extremely difficult to handle.

In operation, the rope 25 is pulled until the anchor engages the pulley 24 where it will clear the deck of the ship, when the arm 8 is swung upwardly to its vertical position. The rope 25 is now moved to cause it to become jammed within the rope jamb 27, whereupon the rope becomes connected with the arm 8 and further movement of the rope to elevate the anchor or swing it to its inactive position on the deck of the ship, will result in the arm 8 being swung vertically over the deck of the ship without further movement of the rope over the pulley 24.

The chain 30 connects with the davit base 6 and arm 8, to regulate or restrict the vertical swinging movement of the arm beyond a predetermined point.

It will be noted that when the anchor has been properly located on the deck of the vessel, the arm 8 may be readily removed by removing the bolt 10, and the davit arm readily stowed where it will be out of the way.

By arranging the davit bases around the vessel at various locations, it will be obvious that the davit may be used or shifted from place to place to facilitate the handling of the anchor.

Having thus described the invention, what is claimed is:

1. In an anchor davit, a base swivelled to the deck of a vessel, a davit arm pivotally connected to said base, said arm embodying an outer and inner section adjustable longitudinally with respect to each other, a pulley mounted at the outer end of the outer section, an anchor rope to which an anchor is secured, operating over the pulley, and a rope jamb mounted on the arm into which said rope is wedged connecting the rope directly to said arm for effecting vertical swinging movement of the arm as said rope is pulled, and a chain secured between the base and arm limiting vertical swinging movement of said arm.

2. In an anchor davit, a base mounted on the deck of a vessel for horizontal swivel movement, a davit arm pivotally connected to said base for vertical swinging movement, a pulley mounted at the outer end of the arm, an anchor rope operating over the pulley and to which an anchor is secured, a rope jamb mounted on the arm adjacent to said pulley into which said rope is removably wedged directly connecting the rope with the arm thereby effecting swinging movement of the arm when the rope is pulled, and a chain restricting vertical swinging movement of said arm.

3. In an anchor davit, a base, a davit arm pivotally mounted on said base and removably connected thereto, a pulley mounted at the outer end of said arm over which a rope operates and to which an anchor is secured, a member connected to said arm having a wedge-shaped opening into which the rope is wedged removably connecting the rope directly to said arm whereby vertical swinging movement is effected when the rope is pulled, and means for restricting vertical swinging movement of said arm.

4. In an anchor davit, a base swivelled to the deck of a vessel, a davit arm pivotally connected to said base, said base having a plurality of spaced openings formed therein, a block having a pin, adapted to be positioned in said openings adjusting and securing the block with respect to the base, said arm engaging said block restricting downward movement of said arm, a pulley mounted at the outer end of the arm, a rope movable over said pulley and to which an anchor is connected, an open ended rope jamb secured to the arm adjacent to the pulley into which the rope is wedged securing the rope directly to the arm whereby vertical swinging movement of the arm is effected when the rope is pulled, and means for restricting vertical swinging movement of said arm.

5. In an anchor davit, a base swivelled to the deck of a vessel, a davit arm comprising outer and inner sections adjustably connected for longitudinal adjustment with respect to each other lengthening and shortening said arm, a pulley mounted at the outer end of the arm, said pulley operating within the confines of the outer ends of said arm, an anchor rope movable over said pulley and to which an anchor is connected, a rope jamb secured to and extending upwardly from the upper surface of the arm, said rope adapted to be moved into said wedge jamb directly connecting the rope to the arm against movement with respect to said arm whereby vertical swinging movement of the arm is effected when the rope is pulled, and a chain connected between the arm and base adapted to limit vertical swinging movement of said arm.

GEORGE P. EVANS.
